UNITED STATES PATENT OFFICE.

WILLIAM CLIMIE, OF AYR, SCOTLAND.

GAS-PRODUCER.

1,327,861.

Specification of Letters Patent.

Patented Jan. 13, 1920.

Application filed February 25, 1919. Serial No. 279,163.

To all whom it may concern:

Be it known that I, WILLIAM CLIMIE, a subject of the King of Great Britain and Ireland and the Isle of Man, and a resident 5 of Ayr, Scotland, have invented new and useful Improvements in Gas-Producers, of which the following is a specification.

This invention has reference to improvements in and relating to gas producers, and 10 comprises an improved arrangement and construction of appliances arranged within the producer for raking and breaking up the fuel so that satisfactory results may be obtained when using fuel which has a tendency 15 to cake in the producer.

When using this caking fuel it has been found in practice that a crust is formed over the fuel and when the ashes are removed from below, the green expanded fuel does 20 not follow which necessitates the application of such appliances for the prevention of channeling through the incandescent fuel.

The object of this invention is to provide a rake which will prevent the formation of 25 this crust so that the full output of gas is obtained from the fuel and all the fuel steadily and automatically finds its way down through the producer through the various zones to the ash pit where the refuse 30 is removed.

According to this invention the rake referred to comprises a crosshead adapted to slide vertically on and to be rotated by a central shaft. This crosshead is provided 35 with appliances comprising toothed rollers adapted to roll on the surface of the fuel and crush the crust of same and teeth adapted to rake up and spread the top surface of the fuel while longer teeth or knives may 40 also be provided to tear through and break up the fuel. A scraper blade may also be arranged and adapted to keep clear the upper surface of the cone shaped air inlet at the lower part of the producer.

45 In order that others skilled in the art to which this invention relates may properly understand the same I have hereunto appended two sheets of explanatory drawings in which Figures 1 and 2 are respectively 50 elevations at right angles to each other of a rake constructed according to the improvements of this invention, with the producer casing shown broken away.

Referring to said drawings:—

55 In carrying the improvements of this invention into effect or practice a crosshead *a*

is slidably mounted on a vertical shaft *b* arranged centrally in the producer *c*. This shaft *b* is rotated at the desired speed by suitable driving means, such as gear wheels *b'* and *b''* driven from a prime moving shaft *b'''*, arranged above the producer.

The shaft *b* is of hexagonal or other polygonal shape in section so that as the shaft is rotated the crosshead *a* is rotated 65 also, while the crosshead is capable of sliding vertically up and down on the said shaft *b*.

This crosshead is preferably formed in two parts secured together by bolts or the like *d* passing through flanges or lugs *e* on each part. Horizontally projecting rods *f* are secured to the crosshead *a*, preferably two, diametrically opposite each other, and these rods *f* are provided with toothed rollers *g* which rest on the fuel and are rotated on their rods *f* by their teeth *h* gripping or digging into the fuel as the crosshead *a* is rotated by the central shaft *b*. It will thus be seen that the rollers *g* travel over the surface of the fuel and as there are three rollers arranged at different distances from the central shaft *b* it will also be seen that the full surface of the fuel is operated upon.

Other rods, bars or the like *i* are also secured to the crosshead *a* preferably two rods diametrically opposite each other and at right angles to the rods *f* carrying the rollers *g*. These latter rods *i* are provided with plates or the like *j* having downwardly 90 projecting teeth or the like *k* so that the said latter rods and plates are rotated around the central shaft *b* by means of the crosshead *a* the teeth *k* rake up the upper surface of the fuel and scatter or spread 95 same. The plates *j* are preferably loosely mounted on the rods *i* so that should the teeth *k* meet a hard or stiff piece or cake of fuel they will rise up and mount or be dragged over that hard piece. The rods *i* 100 may also be provided with a plurality of downwardly projecting long teeth or knives *l* fixed on the shaft to assist in preventing the formation of the crust or cake by cutting or tearing through the fuel to a suitable depth. There are preferably three of these long teeth or knives *l*.

The lower end of the central shaft *b* may also be provided with a crosshead *m* having a scraper blade or knife *n* which as 110 the shaft *b* is rotated passes over the upper surface of the central cone *o* usually ar-

ranged at the bottom of the producer and provided with air inlets for the supply of air to the producer.

Suitable means such as a chain *p* or the like attached to the crosshead *a* through the medium of bars *q* and *r* extending from the crosshead through the roof of the producer may be provided for raising the crosshead *a* and its fittings to the upper part of the producer when desired for instance when it is desired to clean the central shaft from carbon.

The crosshead *a* and its fittings (that is the rake) rests and operates upon the surface of the fuel which slowly falls down the producer as gasification takes place and the refuse is withdrawn in the usual manner and upon a fresh charge of fuel being introduced into the producer from above the rollers cause the rake to mount over the fresh fuel so that the rake automatically maintains its position on the top of the fuel.

What I claim and desire to secure by Letters Patent is:—

1. A gas producer comprising a casing, a fuel rake arranged therein, a device for imparting a traveling movement to said rake over the surface of the fuel, and toothed crushing rolls carried by the rake structure, said rolls tending to maintain the rake at the top surface of the fuel and to crush the crust thereof.

2. A gas producer comprising a casing, a fuel rake having teeth arranged to penetrate

the top surface of the fuel and having toothed crushing rolls rotatably mounted on the rake structure, said rolls tending to maintain the rake at the top surface of the fuel and to crush the crust thereof.

3. A gas producer comprising a casing, a vertical shaft disposed therein, a crosshead mounted on said shaft and having outwardly extending arms, teeth on one of said arms, and toothed rolls on another of said arms.

4. A gas producer comprising a casing, a central shaft therein, a crosshead on said shaft having four radial arms extending therefrom, one pair of opposite arms having toothed rollers thereon and the other pair of arms having teeth.

5. A gas producer comprising a casing, a vertical shaft disposed therein, a crosshead having four uniformly-spaced arms extending therefrom mounted and adapted to be rotated upon said shaft, teeth upon one pair of oppositely disposed arms, and toothed crushing rolls upon the other pair of oppositely disposed arms, said rolls being arranged at different distances from the center of rotation of said crosshead.

In testimony whereof, I have signed my name to this specification in the presence of two subscribing witnesses.

WILLIAM CLIMIE.
